UNITED STATES PATENT OFFICE.

CHARLES R. SMEAD, OF HASTINGS, MINNESOTA.

DESIGN FOR A PEN-BOX, DESK-TRAY, AND PAPER-WEIGHT.

No. 39,729.

Specification for Design.

Patented Dec. 29, 1908.

Application filed September 4, 1908. Serial No. 451,756. Term of patent 3½ years.

To all whom it may concern:

Be it known that I, CHARLES R. SMEAD, a citizen of the United States, residing at Hastings, in the county of Dakota and State of Minnesota, have invented a new, original, and ornamental Design for a Pen-Box, Desk-Tray, and Paper-Weight, of which the following is a specification, reference being had to the accompanying drawing, forming a part thereof.

The figure is a perspective view of a pen box, desk tray and paper weight, showing my new design.

I claim:

The ornamental design for a pen box, desk tray and paper weight, substantially as shown.

CHARLES R. SMEAD.
